UNITED STATES PATENT OFFICE.

GEORGE M. CLARK, OF CHARLESTON, WEST VIRGINIA.

SPIKE PULLER.

Application filed February 11, 1922. Serial No. 535,874.

To all whom it may concern:

Be it known that I, GEORGE M. CLARK, a citizen of the United States, residing at Charleston, in the county of Kanawha and State of West Virginia, have invented new and useful Improvements in Spike Pullers, of which the following is a specification:

This invention relates to improvements in tools, an object being to provide a tool which 10 is capable of use either as a spike puller or as a lifting jack.

Another object of the invention is the provision of a tool of the above stated character which is especially adapted for pulling rail-road spikes and which may be adjusted to 15 rest upon uneven surfaces and supported in a vertical position or in an inclined position, so that the tool may exert a direct pull upon a spike irrespective of the manner in which 20 it has been driven.

Another object of the provision of a spike puller having a novel arrangement of gripping jaws, together with means for conveniently operating said jaws to grip or release a spike.

With the above and other objects in view, the invention further includes the following novel features and details of construction, to 30 be hereinafter more fully described, illustrated in the accompanying drawings and pointed out in the appended claims.

In the drawings:—

Figure 1 is an elevation of a combined spike puller and lifting jack shown in position for pulling a spike.

Figure 2 is an elevation at right angles to Figure 1.

Figure 3 is an enlarged fragmentary sectional view on the line 3—3 of Figure 1.

Figure 4 is a transverse section on the line 4—4 of Figure 1.

Figure 5 is an enlarged fragmentary elevation showing the lower end of the rack bar and the spike gripping jaws carried thereby.

Figure 6 is a fragmentary elevation of the upper end of the tool looking at the side opposite that shown in Figure 1.

Figure 7 is a fragmentary elevation of the lower end of the tool showing the latter arranged for pulling a spike which has been driven at an inclination.

Figure 8 is a similar view showing the tool arranged for pulling spikes between a main rail and a guard rail.

Figure 9 is a detail view of the operating handle for the tool.

Referring in detail to the drawings, wherein like characters of reference denote corresponding parts, the invention is illustrated as comprising a housing which includes spaced side walls 10 which are connected along one edge by a wall 11, the said walls 10 being connected along their opposite edges by a bar 12 which is arranged at the upper end of the housing by a bar 13, the latter connecting extensions 14 of the walls 10 and providing brackets for a purpose hereinafter apparent.

Extending downwardly from one side wall 70 of the housing is a rigid leg 15 which carries at its lower end a foot 16, the said foot and leg being connected by a web 17 to provide a rigid reinforcement. The foot 16 has extending along one edge a flange 18. Extending 75 from the opposite side of the housing is a downwardly inclined offset arm 19 and this arm is provided at one end with an opening for the passage of an adjustable leg 20. The leg 20 is in the form of a rack bar, 80 being provided along one side edge with spaced teeth 21 and these teeth are adapted to be engaged by a dog 22. The dog 22 extends through an opening provided in the outer end of the arm 19 and is carried by a 85 substantially U-shaped yoke 23. This yoke is slidingly mounted upon the outer end of the arm 19 and for this purpose is provided at its opposite ends with slots 24 which engage over pins 25. The dog 22 is yieldingly 90 held in engagement with the teeth 21 by means of springs 26, one end of these springs being connected to the yoke 23 while their opposite ends are connected to the pins 25. Extending from the lower end of the yoke 95 20 is a foot 27.

Slidable within the housing is a bar 28 which is provided along one side with spaced rigid teeth 29. This bar is guided for longitudinal movement within the housing and for this purpose is provided with oppositely extending tongues 30 which slide in grooves 31 formed on the inside of the side walls 10 of the housing. The upper end of the bar 28 is provided with a seat 32 to permit of 100 the use of the tool of the lifting jack.

The bar 28 is provided with a longitudinal passage 33 and slidable longitudinally within this passage is a bar 34 which forms the shank of a gripping jaw 35 which is 110

rigid thereto. An extension 36 projects downwardly from the end of the bar 28 to provide an increased guide surface for the shank 34. Pivotally secured to the jaw 35 as shown at 37 is a jaw 38 and this jaw and the jaw 35 are each provided with a bill 39 for engagement beneath the head of a spike as illustrated by the dotted lines in Figure 5 of the drawings. The upper end of the jaw 38 has pivotally connected thereto one end of a link 40 while the opposite end of this link is pivotally connected to an ear 41 carried at the lower end of the bar 28. It will be apparent from the foregoing description and accompanying drawings, that any upward movement of the bar 38 will cause the bills 39 of the jaws 35 and 38 to tightly engage and grip beneath the head of a spike or similar implement and that a continued pulling action would serve to increase the gripping action, so that the spike would be positively held between the jaws during the operation of the tool. After a spike has been pulled it will remain engaged between the jaws until manually released, so that the invention is especially useful in pulling spikes upon trestles or other elevated structures, whereby the loss of the spikes will be prevented. Extending from the upper end of the shank 34 is an operating handle 42, by means of which the said shank may be moved longitudinally either to open the jaws for engagement over the head of the spike preparatory to pulling, or to release the spike after the pulling operation. Normally this handle 42 is seated within a notch 34 provided in the upper end of the bar 28.

Pivotally mounted upon the housing as shown at 44 is a rectangular yoke 45 and mounted in bearings provided in this yoke is a rock shaft 46. This rock shaft has secured thereon a dog 47, which may be termed the lifting dog, while extending from one end of the rock shaft 46 is a crank arm 48. Mounted in bearings provided in the brackets 14 is a rock shaft 49 which has secured thereon a dog 50, which may be termed the holding dog in that it prevents retrograde movement of the bar 28 after the release of the lifting dog 47. Extending from one end of the rock shaft 49 is a crank arm 51 and this crank arm is connected to the crank arm 48 by means of a link or bar 52, the latter being in turn pivotally connected to the yoke 45 as shown at 53. The connection between the bar 52 and the crank arm 48 includes a pin 54 which is slidable within a slot 55 provided in the bar 52 so as to permit of a sliding pivotal movement between the crank arm 48 and the bar. The yoke 45 is provided with an extension 56 which is received within the socketed end 57 of a bar 58, the opposite end of the said bar being provided with a tapered slot 59 whose side edges are 65 beveled to form a claw for engagement be-

neath the head of a spike. The bar 58 may thus be used as a spike puller.

When it is desired to raise the bar 28, the handle 58 is operated to move the yoke 45 upon its pivot 44. The lifting dog will engage beneath one of the teeth 29 of the bar 28 so as to elevate the latter, when the limit of upward movement is reached, the holding dog 50 will then engage beneath another of the teeth. The dog 47 may then be released and moved downward for re-engagement. By connecting the crank arms 48 and 51 of the dogs 47 and 20 respectively, the said dogs may be simultaneously released so as to permit the bar 28 to be quickly moved to proper position for engagement with a spike. By means of the pin and slot connection 54 and 55 between the crank arm 48 and bar 52, sufficient independent movement between the dogs is provided to permit them to properly perform their function.

The invention is susceptible of various changes in its form, proportions and minor details of construction and the right is herein reserved to make such changes as properly fall within the scope of the appended claims.

Having described the invention what is claimed is:—

1. A tool of the class described comprising a housing, means whereby the housing may be supported in vertical position, a rack bar movable in said housing, pivotally connected gripping jaws, a shank rigid with one of the jaws and slidable longitudinally through the rack bar, a link having one end pivotally secured to the other jaw and its opposite end pivotally connected to the rack bar and means whereby the rack bar may be operated.

2. A tool of the class described comprising a housing, means whereby the housing may be supported in vertical position, a rack bar movable in said housing, gripping jaws carried at the lower end of the rack bar, a yoke surrounding the housing and pivotally mounted thereon, a lifting dog carried by the yoke for engagement with the teeth of the rack bar, a holding dog mounted upon the housing, a link pivotally mounted upon the yoke and having one end pivotally connected to one of the dogs and means for pivotally and slidably connecting the opposite end of the link to the other dog to permit both simultaneous and independent movement of the dogs.

3. A tool of the class described comprising a housing, means whereby the housing may be supported in vertical position, a rack bar movable in said housing, pivotally connected gripping jaws carried by one end of the rack bar, means including pivotally mounted dogs located at the opposite end of and engageable with the rack bar for actuating said bar, means whereby one of

said dogs may be manually operated and means connecting the manually operated dog with the other dog, whereby said dogs may be simultaneously actuated to release 5 the rack bar.

4. A tool of the class described comprising a housing, a rack bar movable therein, means whereby the rack bar may be operated, gripping jaws carried by one end of 10 the rack bar, a rigid leg extending from one side of the housing, a foot extending laterally from said leg, an arm extending

from the opposite side of the housing, a rack bar movable through a guide opening provided in the outer end of the arm and defining an adjustable leg and a spring actuated dog including a U-shaped guide member 15 slidable upon the arm and engaging the teeth of the last mentioned rack bar to hold the adjustable leg in position. 20

In testimony whereof I affix my signature.

GEORGE M. CLARK.
